Primary Examiner — Eric Goodman*Assistant Examiner* — Brett Miller(74) *Attorney, Agent, or Firm* — Myers Wolin, LLC(57) **CLAIM**

The ornamental design for a combinable container, as shown and described.

DESCRIPTION

FIG. 1 is a front perspective view of a first embodiment of a combinable container;

FIG. 2 is a top view thereof;

FIG. 3 is a left side view thereof, the right side being identical;

FIG. 4 is a front view thereof; and,

FIG. 5 is a bottom view thereof.

The broken lines depict environmental subject matter and form no part of the claimed design.
